UNITED STATES PATENT OFFICE.

CHARLES J. WRIGHT, OF CLEVELAND, OHIO, ASSIGNOR TO THE HARRIS AUTOMATIC PRESS COMPANY, OF CLEVELAND, OHIO, A CORPORATION OF OHIO.

PRINTING PRESS.

Application filed October 7, 1921. Serial No. 506,138.

To all whom it may concern:

Be it known that I, CHARLES J. WRIGHT, a citizen of the United States, and a resident of the city of Cleveland, in the county of 5 Cuyahoga and State of Ohio, have invented certain new and useful Improvements in Printing Presses, of which the following is a specification, reference being made to the accompanying drawings, forming a part 10 thereof.

My invention relates more particularly to rotary printing presses of the two-color type, and the object of my invention is, among other things, to provide 15 a simple yet effective means to obtain accurate registration of the colors which are being printed on the paper. I accomplish this object by mounting the transfer cylinder so as to be transversely shiftable on 20 its support, and I further provide means for slightly shifting such transfer-cylinder laterally in either direction to a predetermined requirement, and then maintaining such 25 means in the correct position to obtain proper registration of the colors on the paper that is being printed while the press continues in operation.

The accompanying drawings show the embodiment of my invention in a two color 30 "off-set" press, the same serving to fully explain the invention, which is not restricted, however, to any particular form of rotary presses, since my improvement is equally applicable to a two cylinder press 35 in which the two impression cylinders are connected by a shiftable transfer cylinder, or to other types of presses.

In the drawings Figure 1 is a skeleton 40 side elevation view of a two-color "off-set" press connected by a transfer cylinder which may be transversely shifted to illustrate my invention;

Figure 2 is an enlarged sectional view 45 taken on the line 2-2 of Fig. 1 looking in the direction of the arrow;

Figure 3 is a section taken on the line 3-3 of Fig. 2 looking in the direction of the arrow; and

Figure 4 is an enlarged section taken on 50 the line 4-4 of Fig. 2 looking in the direction of the arrow.

Similar numerals refer to similar parts throughout the several figures.

Referring to the construction shown in 55 Figure 1, the frame-work 5 supports the

bearings of the two plate or form-cylinders 6 and 7, the two rubber cylinders 8 and 9, and the two impression-cylinders 10 and 11. Between the two impression-cylinders 10 and 11 is arranged the transfer-cylinder 12 mounted on the shaft 13 journalled in the frame 5, the cylinder 12 being slightly shiftable in either direction on the shaft 13 which has the gear 14 (Fig. 2) to enmesh with the gears (not shown) of the cylinders 10 and 11. The cylinders 10, 11 and 12 have the grippers 10^a, 11^a and 12^a respectively, carrying and releasing the successive sheets in suitable timed relation. All seven cylinders 60 are relatively arranged with respect to each other as shown in Fig. 1, and are geared 65 together to rotate in unison.

Referring more particularly to Figs. 2, 3 and 4, I have secured to the inner side of the frame 5 the bracket 15 on which is rigidly secured the upper and larger portion 16 of a circular guide plate 17 through which the shaft 13 loosely passes as shown in Fig. 3. The lower and smaller portion 18 is pivotally secured to the portion 16 by pins 70 19 so that this lower portion 18 may be moved transversely of the press, such parts 75 comprising an adjustable-throw-cam. The transfer-cylinder 12 has secured to its left-hand end (Fig. 2) the bracket 20 on which are rotatably mounted two spaced-apart 80 rollers 21 and 22 so arranged that each roller bears frictionally on opposite sides of the guide plate 17 as shown in Fig. 2. When the cylinder 12 is revolved the rollers 21 and 22 travel in a circular path within the edge 85 of the guide plate 17 as shown in Figs. 2 and 3.

Means are provided to move the lower 90 portion 18 transversely on the pins in either direction at will and to any predetermined 95 inclination: The portion 18 has affixed thereto the bracket 23 to which is pivoted the screw-bolt 24 extending outwardly through an opening formed in the frame 5 100 as shown in Fig. 2. Threaded on the bolt 24 is the gear wheel 25 which is journalled in the frame 5 and rotated by a worm 26 mounted on the shaft 27 journalled in the brackets 28 secured to the frame 5. The 105 worm 26 is turned in either direction by the handle 29 secured to the shaft 27 as shown. Mounted on the inner end of the gear wheel 25 is the plate 30 having the segmental slot 31 cut therein within which 110

slot is the pin 32 affixed to the frame 5 as shown in Figs. 2 and 4. This pin and slot arrangement limits the rotation of the gear wheel 25 in either direction by the pin engaging with the ends of the slot. The outer surface of the gear wheel 25 preferably has the graduated scale marks 33 cut therein to coact with the indicator or pointer 34 suitably secured to the frame 5 to enable the operator to set the lower portion 18 of the guide plate 17 at any predetermined inclination in order to shift the cylinder 12 accordingly.

The method of operating my improved attachment during the operation of the press is shown in Fig. 2: When the cylinder 12 is rotating in the position shown in full lines, the lower portion 18 of the guide plate 17 is in direct vertical alinement with the fixed upper portion 16 and the rollers 21 and 22 are revolving each in vertical mutually parallel planes on either side of the guide-plate 17 all as shown in full lines in Fig. 2. Should it be necessary in securing correct registration of the two colors to slightly shift the cylinder 12 to the left on the shaft 13 as shown in dotted lines, the operator turns the handle 29 to rotate through several degrees the gear wheel 25 by means of the worm 26, thereby moving the screw-bolt 24 to the left and slightly swinging the lower portion 18 to the left, all as shown in dotted lines. When the rollers 21 and 22 ride on the outer margin of this portion 18 they immediately move slightly the cylinder 12 to the left as shown by dotted lines in Fig. 2 which will obtain correct registration of the colors; in like manner the cylinder 12 may be shifted to the right by turning the handle 29 in an opposite direction. The pin 32 engaging either end of the slot 31 prevents the operator from unduly turning the gear wheel 25, and the scale 33 and indicator 34 enable him to set such wheel at an accurate predetermined amount so as to obtain precise registration of the colors used on the press.

The shifting of the cylinder 12 to its predetermined position begins after the printing is complete for the first color, and such transverse movement is completed before the leading edge of the sheet having the first color is released and transferred to the impression cylinder for the second color. Furthermore the cylinder 12 is restored to its normal transverse position before the leading edge of the next successive sheet is transferred to the cylinder 12, all irrespective of the direction or extent of the shifting of such cylinder.

My invention, in its broader aspects, is not limited to the particular construction and arrangement of cylinders and parts shown, as many changes may be made without departing from the main principles of

the invention and without sacrificing its chief advantages. Furthermore my improvements may be used on any multicolor press having a single impression-cylinder coacting at different periods with two printing surfaces, the impression-cylinder being shifted between the two printing impressions.

I claim as my invention:

1. In a printing-press, a pair of sheet-carrying members, and an interposed coacting sheet-carrying member laterally shiftable on its transverse support. 75

2. In a printing-press, a pair of sheet-carrying members, and an interposed coacting transfer-cylinder, and means for shifting said transfer-cylinder laterally with respect to the pair of sheet-carrying members. 80

3. In a printing-press, a pair of sheet-carrying members, and an interposed coacting transfer-mechanism, and means for shifting in either direction said transfer-mechanism laterally with respect to the pair of sheet-carrying members at will. 85

4. In a printing-press, a pair of sheet-carrying members, and an interposed coacting transfer-cylinder, and means for shifting said transfer-cylinder laterally with respect to the pair of sheet-carrying members while the press is in operation. 90

5. In a printing-press, a pair of sheet-carrying members, an interposed coacting transfer-cylinder, and means for shifting in either direction said transfer-cylinder laterally with respect to the pair of sheet-carrying members while the press is in operation. 100

6. In a two-color printing press, a pair of impression-cylinders, an interposed coacting transfer-cylinder, and means for shifting in either direction said transfer-cylinder transversely with respect to said impression cylinders while the press is in operation. 105

7. In a two-color printing press, a pair of impression-cylinders, an interposed coacting transfer-cylinder, means for shifting in either direction said transfer-cylinder transversely with respect to said impression cylinders while the press is in operation, and means to limit the action of said shifting means in either direction. 115

8. In a printing-press, a pair of sheet-carrying members, an interposed coacting transfer-cylinder, means comprising an adjustable-throw-cam to shift said transfer-cylinder with respect to said pair of sheet-carrying members, and means to regulate the throw of said cam to any predetermined 120 inclination whereby the shifting of the transfer-cylinder may be fixed to a predetermined amount.

9. In a printing-press, a pair of sheet-carrying members, an interposed coacting 125

130

- transfer-cylinder, means comprising an adjustable-throw-cam to shift said transfer-cylinder with respect to said pair of sheet-carrying members, means to regulate the throw of said cam to any predetermined inclination whereby the shifting of the transfer-cylinder may be fixed to a predetermined amount, and means to limit the action of said shifting means in either direction.
10. In a two-color printing press, a pair of impression-cylinders, an interposed coacting transfer-cylinder, and means comprising an adjustable-throw-cam acting on said transfer-cylinder for moving the latter transversely with respect to said impression-cylinders.
11. In a two-color printing press, a pair of impression-cylinders, an interposed coacting transfer-cylinder, and means comprising an adjustable-throw-cam acting on said transfer-cylinder to move the latter transversely in either direction with respect to said impression-cylinders and to hold same in any predetermined position.
12. In a printing-press, a pair of sheet-carrying members, an interposed coacting transfer-mechanism and means for laterally shifting said transfer-mechanism during a predetermined portion of its rotation with respect to the pair of sheet-carrying members.
13. In a printing-press, a pair of sheet-carrying members, an interposed coacting transfer-cylinder and means for laterally shifting said transfer-cylinder a predetermined distance during a predetermined portion of its rotation with respect to the pair of sheet-carrying members.
14. In a printing-press, a pair of sheet-carrying members, an interposed coacting transfer-cylinder and means for transversely shifting said transfer-cylinder a predetermined distance during one part, and for returning same to its original position during another part, of its rotation.
15. In a printing-press, a rotatable sheet-carrying cylinder, and means for reciprocating said cylinder transversely with respect to the press during each revolution of said cylinder.
16. In a printing-press, a rotatable sheet-carrying cylinder, and means for shifting said cylinder transversely in both directions with respect to the press during each revolution of said cylinder.
17. In a printing-press, a rotatable sheet-carrying cylinder and automatic means for transversely shifting said cylinder a predetermined distance in both directions with respect to the press during each revolution of said cylinder.
18. In a printing-press, a rotatable sheet-carrying cylinder and means operable during each revolution of said cylinder to shift the cylinder transversely to a predetermined position and to restore said cylinder to its original position.
19. In a printing-press, a rotatable sheet-carrying cylinder, means for transversely shifting said cylinder a predetermined distance during a predetermined portion of its rotation, and means for returning said cylinder to its original transverse position during another predetermined portion of said rotation.
20. In a printing-press, a rotatable sheet-carrying cylinder, means for shifting said cylinder to different transverse positions with respect to the press during each revolution thereof while carrying and releasing the sheet.
21. In a multi-color printing-press, a printing couple for printing a sheet in one color, means for thereafter laterally shifting the sheet less than its width with respect to said printing couple, and separate means for thereafter printing another color on the sheet.
22. In a multi-color printing-press, a printing couple for printing the first color on the sheet, means for thereafter shifting said sheet a predetermined distance less than its width laterally with respect to said printing couple, and separate means for thereafter printing another color on the sheet.
23. In a multicolor printing-press, a printing couple for printing a design on the sheet, means for laterally shifting the sheet less than its width after said printing with respect to its path of travel through the press, and separate means for thereafter printing another design on the sheet.
24. In a multicolor printing-press, a printing couple for printing a design on a sheet of stock, means for holding the sheet while being so printed, means for transversely shifting said holding means and said sheet with respect to its path of travel, and separate means for thereafter printing another design on the sheet.

CHARLES J. WRIGHT.
